UNITED STATES PATENT OFFICE.

FREDERICK W. FAHRENFELD, OF CHICAGO, ILLINOIS, ASSIGNOR TO AUTOMATIC ELECTRIC COMPANY, OF CHICAGO, ILLINOIS, A CORPORATION OF ILLINOIS.

CALLING-DEVICE ATTACHMENT.

Application filed May 1, 1920. Serial No. 378,242.

To all whom it may concern:

Be it known that I, FREDERICK W. FAHRENFELD, a citizen of the United States of America, and a resident of Chicago, Cook

5 County, and State of Illinois, have invented certain new and useful Improvements in Calling-Device Attachments, of which the following is a specification.

My invention relates in general to an 10 attachment for a calling device and more specifically to a calling device ring or protecting casing which is adapted to be applied to a standard calling device to protect the same.

15 Among the objects of my invention are to provide an easily attached and easily removable protecting ring or case for a calling device dial which may be attached either only for shipment or while the dial is in use and effectually prevents the usual knocks or blows, to which the device may be subjected, from bending the finger hole dial of the device or otherwise defacing or damaging the device.

20 25 This is especially useful when the calling device is to be used by an operator whose device is usually mounted in the handiest place for use and therefore where it is often likely to receive a number of severe knocks 30 while the operator changes plugs in putting up connections. As is well known to the art, the finger hole dial of the common type of calling device is pivoted at its center point and its outer edge or rim is con-

35 siderably weakened by having the finger holes therein, the holes being used to rotate the dial in transmitting impulses. It will be seen also that any blow on the rim of the finger hole dial is likely to cause considerable damage, either by defacing the same or by bending either the dial or its pivot post so as to render its free rotation impossible.

In the drawings I have shown in Figures 45 1 and 2 the ring clamped or sprung into position on the calling device and in Figure 3, I have shown a perspective view of the protecting ring showing how it is formed to fit on the calling device.

50 The ring 1 of my invention is formed of steel, preferably black enameled, and being open at one side to allow it to be forced apart sufficiently to snap it over the plate 2 of the calling device. In the front view

(Fig. 1) may be seen the upper edge of the 55 ring lying just outside the edge of the finger hole dial 3 and fitting closely around the finger stop 4.

Figure 2 is a side view of only the essential parts of a standard calling device, with 60 the ring cut in half and shown in cross section. This figure shows how the curved portion 5 of the ring fits over the back plate 2 of the calling device to hold the ring in position.

65 In Figure 3 the shape of the ring may be clearly seen, showing the inner and outer surfaces of the curved portion 5 and the opening 6 which is just large enough to fit over the finger stop 4 when in position. It 70 will be understood that the inner diameter of the ring above the enlarged or curved surface 5, is smaller than the diameter of the plate 2 so that the ring must be sprung outward in order to be attached. However, 75 the plate 2 fits snugly into the curved portion 5 and is there held by the projecting surface 7 against movement.

In Figure 2 it will be seen that the upper or front edge of the ring lies just back 80 of and a slight distance away from the outer front edge of the finger hole dial, so that the dial may rotate freely and may yet be protected from damage.

Having described the features of my invention what I consider to be new and desire to have protected by Letters Patent will be pointed out in the appended claims.

What I claim as my invention is:

1. A tensioned protecting ring for a calling device, formed from steel and having a groove adapted to engage the outer edge of said device under its own tension, to protect the finger-hole dial and prevent the bending or damaging of said dial.

90 95 2. In a calling device having a plate and a finger hole dial pivoted therein, a removable casing or protecting ring tensioned to clamp tightly about said plate and in such a position as to protect the dial from accidental blows.

100 105 3. In a calling device having a plate and a finger hole dial pivoted therein and rotatable about an axis, a finger stop for limiting the movement of the dial, and a detachable ring or casing formed of steel and adapted to be sprung into place around said plate and being held in place by the plate

and the finger stop, said ring projecting up to and around the free edge of the finger hole dial to protect the same without interfering with its operation.

5. 4. In a calling device having a supporting plate carrying a rotatable finger hole dial, a finger stop, a ring formed of spring steel and having a concave surface on the inner side thereof adapted to fit snugly over said plate and cut out portions in said ring which fit over the finger stop to prevent the ring from slipping.

5. A protecting ring for a calling device, which is removable and is held in place only by its own tension said ring lying around the outer edges of the finger hole dial to protect the same.

6. A protecting ring for a calling device formed of heavy spring steel and having an opening in one side thereof which permits

its being sprung open to be attached or removed from the calling device.

7. A protecting ring for a calling device formed of heavy spring steel and having an opening in one side thereof which permits 25 its being sprung open to be attached or removed from the calling device, said opening being formed to fit snugly over the finger stop of the dial to hold the ring in place.

8. In a calling device having a supporting plate carrying a rotatable dial and a finger stop, a protecting rim of steel adapted to be sprung into position around said plate with its forward edge lying just outside and around the outer edge of the dial, and held there solely by its own tension.

Signed by me at Chicago, Cook County, Illinois, this 26th day of April, 1920.

FRED. W. FAHRENFIELD.
